VENETIAN BLIND SLAT RETAINER

Brooks Walker, Piedmont, Calif.

Application November 6, 1948, Serial No. 58,765

6 Claims. (Cl. 160—178)

1

This invention pertains to improvements in the methods of securing slats to ladder tapes in Venetian blinds when the slats are to be removable by the use of offset lifting cords as shown in my U. S. Patent No. 2,200,349.

The invention pertains primarily to the use of sliding members such as wires which are secured for sliding movement to the Venetian blind slat by forming suitable offset punches in metal slats to receive the sliding member or by a hole punched in the slat through which the sliding member passes for rotational sliding movement. With apertures in the slats through which the cross members may be inserted by pressing the cross member upwardly with the finger, the sliding member can be inserted under the cross member where it rises through the aperture to secure the slat suitably to the cross member in a positive manner, at the same time allowing a sliding movement of the slat relative to the cross member for proper alignment between the side members of the ladder tapes and the positioning of the slat on the ladder rung for the most effective closing of the slats in the two tilted positions of the slats.

Further objects of the invention will be made clear in the attached specifications, drawings, and claims.

I have illustrated my invention by way of example in the accompanying drawings, in which:

Figure 1 is a perspective view, partly cut away, showing a portion of a slat on a portion of the ladder tape and the means for securing the same.

Figure 2 is a partially cut away perspective view showing another form of the invention.

Figure 3 is a perspective view showing a section of a wooden or composition slat and a section of the supporting ladder tape showing another form of the invention.

Figure 4 is a perspective view of a portion of a metallic slat and a portion of a ladder tape, including a form of the invention similar to that shown in Figure 3.

In all views, like numerals of reference refer to corresponding parts throughout said views.

In Figure 1, I have shown a ladder tape 10 with sides at each edge of the slats 15 which it supports in spaced relationship in any conventional manner. The slat has two cut-out portions 16 and 17 which may be round, oblong, or rectangular and are adapted to receive a portion of the ladder rung 11 when the same is pushed through the opening by the operator's fingers when the slats are to be attached to the ladder rung. The slat is pierced and offset at 15a and 17a to form a suitable opening and bearing for

2

locking pins 17 and 22 which may be formed of wire with a rounded end which will not scratch or pierce the operator's finger and will not catch on the ladder rung when the same is inserted.

5 The spring tension between the double portion of the locking pins 22 and 17 where they pass through the pierced portion of the slat 15a and 17a, respectively, keep the pins in their desired position relative to the slat during the normal operation of the blind.

When it is desired to disengage the slat for cleaning or painting or other purposes, pin 17 is retracted and the ladder rung at the right-hand side of the ladder tapes on which slat 15 rests

15 is released and the slat can be removed, it being necessary to have only one pair of pins 17 and 22 adjacent to one ladder rung regardless of whether there are two or more ladder tapes in a blind. Stabilization of slat 15 relative to one

20 ladder tape at 10 is sufficient for retention of the slat. Since the ladder rungs are mostly staggered, it may be desirable to provide two pins as shown at 17 and 22 so that the slats will not have to be sorted for the right and left-hand positioning

25 of ladder rungs where all the slats are to be secured to one ladder tape. However, if double ladder rungs are used, only one pin in one position on all slats may be necessary in order to engage the ladder rung at one side of the tape.

30 The slats with one hole and one pin can be reversed in position and one pin used to engage the ladder rungs at alternate ladder tapes, thereby requiring only one hole and one pin per slat.

In Figure 2, I have shown an alternate construction in which ladder tape 10 supports slat 30 which has two openings 30a and 30b adapted to receive the ladder rung 11. Locking pin 35 goes through two punched and offset openings in a slat to form a suitable sliding support for

40 the locking pin 35. The two openings 30a and 30b are adapted to overlay correctly the staggered positions of the ladder rungs 11 so that the pin may be slid either to the right or to the left to engage the ladder rungs as they occur in

45 staggered relation underneath the slats. This construction obviously requires only one pin for the staggered ladder rungs rather than the two as shown in Figure 1. However, the handle at the end of the pin for control cannot be quite

50 as large in this construction as when two pins are used. There are some cost and assembly advantages to this construction. Lifting of the blind is accomplished by lift cord 20 in all figures; the lift cords are in the offset position as shown in my U. S. Patent No. 2,200,349.

In Figures 3 and 4, ladder tape 10 supports

the slat 110 by means of cross rung 11 which directly underlies the slat. Rotating locking pin 45 for the wooden or composition slat 110 in Figure 3, or rotating pin 47 for metallic slat 50 in Figure 4, has a curved arcuate end 45a and 47a, respectively, which is preferably curved on a radius about the pivot point of the sliding pin 45 or 47, respectively. This pivot point is preferably equidistant between the two openings 40a and 40b as shown in Figure 3, or equidistant between openings 50a and 50b as shown in Figure 4. The portion of the wire rotating pin 45 which underlies the slat is preferably located so as to point at the midpoint of end 45a to form a suitable bind with the slat so that the pin will stay in any position in which it is desired for retention or non-retention of slat 110 to the ladder rung of the slat supporting tape. By properly forming the pin relative to the pivot point, the pin will engage cross rungs at either opening 40a or 40b. The pin will engage the cross rung at either opening 40a or 40b in Figure 3, or pin 47 will engage the cross rung at openings 50a and 50b in Figure 4. The pin is attached to the slat by inserting the underlying end through the opening in the slat as at 45b, possibly when the end 45a is turned away from the slat. The pin can be slightly bent after inserting in the slat to get the necessary tension, if added tension is needed.

Slat 110 is shown as a wooden slat whereas slat 50 in Figure 4 is shown as a curved metal slat, both of conventional construction. Obviously, paper covered slats or slats of any other contour or material may be used within the scope of this invention. One advantage in the type of construction shown in Figures 1 through 4 is that the slat does not have to be deflected in order to engage and disengage the slat and the cross rung. At the same time, the retention between the slat and the cross rung is very positive and is suitable for use in connection with string ladder tapes as shown as opposed to woven ladder tapes which can be engaged by the slat by the use of tongues as shown in Patent No. 2,311,716 issued to this applicant.

I do not wish in any way to limit myself to the exact details or mode of operation set forth in the specification and drawings, for it will be obvious that wide departure may be made in the way of details without departing from the spirit and scope of my invention which is set forth in the following claims.

I claim as my invention:

1. In a Venetian blind having ladder tapes,

cross rungs and slats, said slats having openings therethrough, a pin movably secured to the slat and positioned as to pass over the said opening, a portion of the cross rung passing up through the slat opening and held in the opening by the pin.

2. In a Venetian blind having ladder tapes, cross rungs and slats, said slats having openings therethrough, a pin movably secured to the slat for sliding movement across and away from the said opening, a portion of said cross rung passing up through the slat opening and held by the pin when across the opening.

3. In a Venetian blind having ladder tapes, cross rungs and slats, said slats having openings therethrough, a pin movably secured to the slat for pivotal movement across and away from the said opening, a portion of said cross rung passing up through the slat opening and held by the pin when across the opening.

4. In a Venetian blind having ladder tapes, cross rungs and slats, said slat having spaced openings therein, a pin movably secured to the slat intermediate of the openings and positioned to pass over one of the openings in either extended position of the pin, a portion of the cross rung passing up through one of the openings and held in the opening by the pin.

5. In a Venetian blind having ladder tapes, cross rungs and slats, said slat having spaced openings therein, a pin movably secured to the slat intermediate of the openings and positioned to slide over one of the openings in either extended position of the pin, a portion of the cross rung passing up through one of the openings and held in the opening by the pin.

6. In a Venetian blind having ladder tapes, cross rungs and slats, said slat having spaced openings therein, a pin movably secured to the slat intermediate of the openings and positioned for pivotal movement across one of the openings in either extended position of the pin, a portion of the cross rung passing up through one of the openings and held in the opening by the pin.

BROOKS WALKER.
